United States Patent Office.

DAVID HARGER, OF DES MOINES, IOWA.

Letters Patent No. 73,889, dated January 28, 1868.

IMPROVED CAR-COUPLING.

The Schedule referred to in these Letters Patent and making part of the same.

TO ALL WHOM IT MAY CONCERN:

Be it known that I, DAVID HARGER, of Des Moines, in the county of Polk, and in the State of Iowa, have invented certain new and useful Improvements in Car-Couplings; and do hereby declare that the following is a full, clear, and exact description thereof, reference being had to the accompanying drawings, and to the letters of reference marked thereon.

In the annexed drawings, making part of this specification, A A represent two jaws, which are pivoted to a bar, C, as seen at $x x$, near their rear ends. These jaws are pressed together by means of the rubber springs B B, which are held in place above and beneath the jaws by means of the bolt a, which passes through the jaws, and also through the centres of said springs. The mouth formed at the forward ends of these jaws is flaring, as seen, and within this mouth is a recess shaped like an arrow-head. D represents the draw-bar, which has a hole in its forward end, and inserted in this hole is a coupling-bar, G. The rear end of this coupling-bar is held in any suitable manner in the opening of the draw-bar, but so that it can revolve or turn in the line of its length when required. An arrow-head is the form of the forward end of the coupling-bar, and said head is made so that it will fit loosely within the recess of similar shape in the jaws A A. H represents a lever-handle, which is secured at one end to the coupling-bar G. The outer end of this lever plays in a metallic or other keeper, I, so that it is allowed to move only such a distance. The jaws being attached to one car, and the draw-bar D to another, when the two approach each other the arrow-head of bar G forces open the jaws A until it enters its recess. The jaws then close upon it and retain it.

To uncouple the cars the bar G is partially revolved until the plane sides of the head are presented between the jaws, then the bar G withdraws very easily by moving back the car. Cars will uncouple very readily with this arrangement in case of accident, such as running off the track and upsetting, &c.

What I claim, is—

The revolving coupling-bar G, when constructed and arranged as herein specified, in combination with the lever H, keeper I, and spring-jaws A A, as and for the purposes herein described.

In testimony that I claim the foregoing, I have hereunto set my hand, this 16th day of November, 1867.

DAVID HARGER.
